(57) **CLAIM**

The ornamental design for a battery pack carriage assembly, as shown and described.

DESCRIPTION

FIG. 1 is a rear perspective view of a second construction of a battery pack carriage assembly.

FIG. 2 is a front view of the battery pack carriage assembly of FIG. 1.

FIG. 3 is a rear view of the battery pack carriage assembly of FIG. 1.

FIG. 4 is a left side view of the battery pack carriage assembly of FIG. 1.

FIG. 5 is a right side view of the battery pack carriage assembly of FIG. 1.

FIG. 6 is a top view of the battery pack carriage assembly of FIG. 1; and,

FIG. 7 is a bottom view of the battery pack carriage assembly of FIG. 1.

The ornamental design which is claimed is shown in solid lines in the drawings. The portions of the design shown in broken lines are included for the purpose of illustrating environment and form no part of the claimed design.
